TO RED CHIEF MANUFACTURING COMPANY, OF LOUISVILLE, KENTUCKY.

GRINDING-MILL BUR.

1,126,976.

Specification of Letters Patent.

Patented Feb. 2, 1915.

Application filed October 21, 1912. Serial No. 727,037.

To all whom it may concern:

Be it known that I, LOUIS E. GAISSER, a citizen of the United States, residing at Louisville, in the county of Jefferson and State of Kentucky, have invented a new and useful Grinding-Mill Bur, of which the following is a specification.

This invention relates to an improvement in grinding burs.

10 The primary object of the invention is to improve the construction shown in the patent granted me Aug. 31, 1909, No. 932,543.

A further object is to provide a flat rotatory bur with ribs which extend entirely 15 thereacross and substantially coplanar throughout their entire length and which ribs are sharpened at their inner extremities in order to cut the grain and are flat at their outer extremities to successfully 20 grind and reduce to the desired state the grain prior to its final ejection from the burs.

A further object is to provide a grinding 25 rotary bur with a plurality of ribs sharpened at their inner extremities and substantially coplanar throughout their entire length and to provide a second set of ribs which are adapted to clean the various 30 spaces intermediate the ribs and to prevent the permanent lodging of grain between the spaces defined by the ribs.

A further object is to provide a plurality 35 of raised lugs extending radial of the flat bur and projecting beyond the outer periphery thereof and which act in the capacity of vanes or sweeps and provide for the proper ejection of the ground material after it has left the ribs.

With the foregoing and other objects in 40 view, which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

50 In the drawing: Figure 1 is a front elevation of the female grinding member. Fig. 2 is a longitudinal sectional view of said member. Fig. 3 is a side elevation of the male grinding member. Fig. 4 is a 55 front elevation of said member. Fig. 5 is

a detail view of the annular member which is secured to the male grinding member. Fig. 6 is a transverse section of said member. Fig. 7 is a cross sectional view taken on the line A—A of Fig. 5.

60 The female grinding member 17 is formed with an opening 18 through which the grain passes to the burs. The member 17 is provided internally with ribs 19 said ribs being continued over the flange 20 of said member.

The stationary conical member 17 is maintained in position by the lugs 21, its reduced end 22 being bored to receive the shaft 12. This female member or what might be 70 termed the cup bur is formed with "leaders" 24, each of which is formed with the "feeders" 25 which cut in such a way as to crush the grain.

The male bur 26 is formed with the conical 75 grinding surface consisting of nine "leaders" 28, each of which is formed with three feeders 29. The number of leaders and feeders however, may be changed so as to suit the grain to be ground. This bur is 80 formed with lugs 30 which extend radially from the cylindrical portion 31 of the bur. The flat rotary bur 32 which corresponds with the flat stationary bur 20 is formed adjacent the opening 33 and on the face 85 remote from the curved ribs with slots which receive the lugs 30 of the conical bur, the flat bur 32 in this manner being locked to the conical bur. The rotary flat bur is formed with four raising ribs 35. The male 90 bur 26, may be formed integral with the shaft, or may be formed separate and held thereto by welding, a set screw, or other suitable means.

As illustrated in Fig. 6 the ribs of the 95 rotary bur extend entirely across the plate and lie in a common plane except at their ends where they dip slightly. The raised ribs 35 lie in a common plane throughout their entire length and terminate in a sharp 100 shoulder at the inner periphery of the annular bur or plate, thus allowing for the entrance of the grain between the flat burs but at the same time insuring that the ribs will grind the material at all times while 105 passing from the inner to the outer extremities of the said ribs.

The plate or body portion of the flat bur extends beyond the surface across which the ribs extend and is disposed below the said 110

surface as at 36. The flat bur 20 illustrated in Fig. 2 is also provided with an outer rim 37 which is disposed below the plane containing the grinding ribs. Thus when the flat burs 32 and 20 are assembled in proper relation and in contact, an annular channel extending around the burs will be defined by the walls or extensions 36 and 37. The said annular channel receives the ground material therein and provides that it will be ejected radially from the burs. The annular channel also provides a protection for the grinding ribs. In order to eject the material from the annular channel and in a radial manner, the lugs 38 are provided as illustrated in Figs. 5 and 6 and which lugs act in the capacity of vanes or sweeps and eject the material from the annular channel in a radial manner, which provides for the proper delivery thereof from the outlet spout of the grinding mill in which the burs herein disclosed are used.

What is claimed is:—

1. A flat bur for grinding mills comprising a plate with a plurality of grinding ribs extending entirely thereacross and coplanar throughout substantially their entire length, said ribs sharpened at their inner extremities and terminating in flat portions at their

outer extremities and dipping slightly out of the said common plane at their inner and sharpened extremities, and a plurality of enlarged ribs coplanar throughout their entire length with the aforementioned ribs and terminating in abrupt shoulders at 35 their inner extremities.

2. A flat bur for grinding mills, comprising an annular plate, said plate provided with a plurality of ribs extending coplanar throughout substantially their entire length and extending entirely across the said plate, the said ribs dipping slightly out of the said common plane at their inner extremities and sharpened at the said extremities and merging into broad flat surfaces at their outer extremities, and a plurality of enlarged ribs extending throughout their entire length in the said common plane and terminating at the inner periphery of said annular plate in abrupt sharpened shoulders.

In testimony that I claim the foregoing as my own, I have hereto affixed my signature in the presence of two witnesses.
